Attorney.

UNITED STATES PATENT OFFICE.

MIMA K. FINLAYSON, OF LOS ANGELES, CALIFORNIA.

FLOWER RECEPTACLE.

Application filed October 6, 1925. Serial No. 60,753.

This invention particularly pertains to a device for holding and supporting flowers in flower-receptacles, such as vases, jars and the like, and has as its primary object the provision of a means whereby the stems of flowers may be engaged and supported adjacent the top of the receptacle.

Another object is to provide a holder which is especially adapted for use as a mounting for short-stemmed flowers whereby such flowers may be attractively arranged in tall receptacles and in containers of such size and shape as are not ordinarily suitable for this purpose.

Another object is to provide a flower holder which embodies a flower-engaging member supported on a standard and adapted to be placed in a tall or deep receptacle and substantially supported on the bottom thereof, and in which the standard is so constructed as to be longitudinally adjustable whereby the flower-engaging member may be positioned at various levels and thereby accommodate the holder for use in receptacles of various heights.

Another object is to provide a simple and effective means whereby the length of the standard may be readily adjusted.

A further object is to provide a stand for displaying flowers which will facilitate artistic arranging and grouping of flowers in a receptacle, and which will impart to shortened stem flowers the appearance of having long stems.

With the foregoing objects in view, together with such other objects and advantages as may subsequently appear, the invention resides generally in the provision of a stand comprising a longitudinally adjustable standard supported on a base member and carrying a flower-engaging member adapted to receive and support the stems of flowers.

The invention further resides in the parts and in the construction, combination and arrangement of parts hereinafter described and claimed and illustrated by way of example in the accompanying drawings, in which:

Fig. 1 is a view in vertical section of the flower-holder showing it as applied to a vase;

Fig. 2 is a view in section showing the flower-holder as employed in conjunction with a bowl or jar;

Fig. 3 is a detail in perspective illustrating fragmentary portions of the adjustable standard as separated;

Fig. 4 is a plan view of a screen or foraminated wall employed in the flower-engaging member;

Fig. 5 is a view in elevation illustrating a modified form of the invention.

Referring to the drawings more in detail, A indicates a base member on which is mounted a standard comprising telescoping members B and C adapted to be adjusted to various positions longitudinally of each other, and D indicates generally a flower-engaging member carried by the standard and which may be of any suitable construction.

The standard member B is cylindrical and is provided adjacent its upper end with a pin projecting laterally therefrom. The standard member C comprises a tube which is formed with a longitudinally extending slot F opening at its lower end whereby the member C may be telescoped over the member B with the pin projecting through the slot F. Leading from the slot F is a series of upturned bayonet slots G which are suitably spaced apart throughout the length of the tube, each of which is adapted to receive and to be engaged by the pin to support the member B on the member C in various vertically adjusted positions.

The flower-holder D is here shown as comprising a shell having a bottom wall H and annular side walls J erected from the bottom wall, which walls may be foraminous as shown in Figs. 1 and 2, but may be imperforate as shown in Fig. 5.

Mounted in the shell formed by the walls H and J is a horizontally extending foraminated wall K spaced a short distance above the bottom wall H and suitably supported on the upper margin of the shell is a second foraminated wall L spaced a suitable distance above the wall K. The walls K and L may be formed of reticulated material, such as screen wire, as shown in Fig. 4, or may comprise perforated plates, and in like manner the walls of the shell may be formed of reticulated material such as screen wire or may comprise perforated sheet material.

Loose weighted rings M are provided on the base member A to stabilize the structure.

A handle or bail N is provided on the shell

by means of which the device may be readily placed in and removed from a receptacle O such as vase, bowl or jar.

In the application of the invention, where the device is formed with a foraminated shell, as shown in Figs. 1 and 2, it is placed in a water containing receptacle, with the base A seating on the bottom thereof and with the shell arranged immediately below the mouth thereof and at least partly submerged in the water; the standard being adjusted to dispose the shell in the desired spaced relation to the bottom of the receptacle. The receptacle O may comprise a vase, bowl or jar but where the receptacle is of such character or size as to render it undesirable to fill it with water, a separate container for the water may be employed, as shown in Fig. 2.

In the same instances, it may be advantageous to employ the shell as a water container, in which event the walls thereof will be imperforate as shown in Fig. 5. This construction obviates the necessity of placing water in the vase or receptacle in which the flower-holder is disposed.

The spaced foraminated walls K and L affords a convenient means for receiving and engaging the stems of flowers; the stems being inserted through the apertures in the upper wall L and then passed through the

apertures in the lower wall, thus effecting engagement with the stem at two points in such manner as to support the stem and securely retain the flower in place. The walls L and K are preferably foraminated throughout so as to permit a varied arrangement and grouping of flowers on the holder.

It will be observed that by use of the device, short-stemmed flowers may be properly supported in tall or deep receptacles and will have the appearance of having long stems.

While I have shown and described a specific embodiment of my invention, I do not limit myself to the exact details of construction set forth but may employ such changes and modifications as come within the meaning and scope of the appended claim.

I claim:—

The combination with a receptacle of a shell adapted to be disposed in said receptacle, means for supporting said shell in spaced relation to the bottom of said receptacle adapted to be adjusted to vary the spacing of said shell in relation to the bottom of the receptacle, means carried by said shell for engaging and supporting the stems of flowers, and a variable weight stabilizing means for the supporting means for the shell.

MIMA K. FINLAYSON.
